C. LEFFLER.
BOX BINDING MACHINE.

No. 576,863.

Patented Feb. 9, 1897.

UNITED STATES PATENT OFFICE.

CHARLES LEFFLER, OF BROOKLYN, NEW YORK.

BOX-BINDING MACHINE.

SPECIFICATION forming part of Letters Patent No. 576,863, dated February 9, 1897.

Application filed April 2, 1896. Serial No. 585,867. (No model.)

To all whom it may concern:

Be it known that I, CHARLES LEFFLER, a citizen of the United States, residing at Brooklyn, in the county of Kings and State of New York, have invented certain new and useful Improvements in Box-Binding Machines, of which the following is a full, clear, and exact description.

This invention relates to machines for binding the corners of boxes with metallic strips.

The invention consists more particularly of the mechanism for feeding the metallic strip and guiding it to the forming and setting dies and to the means for severing the strip at the required length for use.

The machine to which my improvements are applied comprehends a stationary anvil or lower die adapted to receive thereon the corner of a box adjusted thereto after the manner of a saddle and an upper reciprocating die having a V-shaped groove adapted to straddle the corner of the box and the ridge of the lower die and provided with means for holding a section of the metallic binding-strip until it is carried down upon the corner of the box and fastened thereto by the force of the blow against the lower die.

The invention will be described in detail with reference to the accompanying drawings, in which—

Figure 1 is a side elevation of the machine, the lower portion of the base or standard upon which it is mounted being removed. Fig. 2 is a front elevation of the machine. Fig. 3 is an end view of a movable guide for the strip. Fig. 4 is an end view in detail of the upper and lower dies, the corner of the box being shown on the lower die. Fig. 5 shows the corner of the box after the metallic strip has been applied thereto. Fig. 6 is a side view of the feeding-wheel and the strip. Fig. 7 is a section taken on line X X of Fig. 1. Fig. 8 is a plan of a portion of the strip, and Fig. 9 shows a box with the metallic corners as applied thereto by the machine.

Referring to the drawings by letter, A represents the base or standard supporting the machine.

a is a frame secured to the top of the base and having mounted in it transversely a fixed axle or stud B. Upon this stud the operating lever or treadle T is pivotally mounted.

The hub of the treadle carries an arm t, which connects by means of an adjustable link t' with a toggle-lever t². The toggle is connected with a reciprocating piston c, mounted in vertical guides in the frame, carrying at its lower end a die-head d. In the face of the die-head is fixed a hardened-steel bar d', having a V-shaped groove d² formed in it, the sides of which are each provided with grooves d³, partially formed by plates d⁴, fixed to the lower side of the bar, as indicated in Fig. 4. Immediately below the die-head is an anvil e, having a wedge-shaped ridge e', corresponding in angle to the V-shaped groove in the die above it. This anvil is adapted to receive the box and hold it while the metallic strip is being applied to its corners and therefore is made adjustable in length to accommodate different sizes of boxes by mounting it in guideways e² in the frame. A suitable hand-wheel e³ and screw is provided for locking it in any position.

The metallic strip or ribbon which is applied to the corners of boxes is shown in detail in Figs. 4, 6, and 8 and is represented by the letter s. It is merely a strip of tin having a row of perforations s' near to each edge, formed by striking the metal through and leaving a bur or tooth s² under each hole. The strip thus prepared is wound upon a reel and mounted in a frame f at the back of the machine. g represents a transverse shaft mounted at the rear of the machine in the frame a and having rigidly fixed upon it a feeding-wheel g', located midway between the two uprights constituting the frame a and provided with two rows of sprocket-teeth g². Immediately beneath this wheel is a small plate h, carrying two pins h', which project into cavities formed in the frame and serve as vertical guides for the plate. Beneath the plate and located in a socket i is a spring i', which bears continuously against the plate and tends to force it against the periphery of wheel g'. The face of this plate has two lugs h², between which the wheel g' turns. It also has two grooves h³, through which the two rows of sprocket-teeth pass as the wheel rotates. The strip s leads from the reel between wheel g' and plate h, and the sprocket-teeth of the wheel are arranged to take into the respective rows of holes s' in the strip, while the

burs or teeth on the under side of the strip pass through the grooves h^3 in plate h . This is plainly shown in Fig. 7. It will now be understood that when the wheel g' is rotated 5 the strip s will be fed along the plate h , serving to hold the strip up against the wheel and make the feed positive. Upon the shaft g is a ratchet-wheel j , and adjoining the ratchet-wheel and loose upon the same shaft is a pinion k , having an arm k' extending therefrom and carrying a pawl k^2 , which engages with the ratchet-wheel. The ratchet, pinion, and pawl are located outside of the frame of the machine, as shown in Figs. 1 and 7. A reciprocating rack-bar l , engaging with the pinion, 10 is mounted to slide through a box l' , bolted to the side of the frame, and is connected by means of a link m with the free end of arm o , hung loosely upon the stud B , which projects through the frame a for that purpose. 15 This arm is provided with a slot o' . Immediately behind the arm is another arm p , slotted or grooved similarly to arm o . This arm p is fixed upon the end of a shaft p' , 20 mounted transversely in the two sides of the frame a . Between the two parts of the frame this shaft carries a crank p^2 , to the end of which is pivoted a link q , which in turn is connected with an arm r by means of a pin 25 and slot, as shown, the arm r being a radial projection from the hub of the lever T . Arms p and o are pivoted together by means of an adjustable pivot and clamping-nut p^7 . Upon the arm p is a lug p^x , to which a spring p^y , 30 fastened at p^8 , is connected for the purpose of swinging the arm in one direction. This lug p^x is provided with a shoulder p^3 , with which a pawl p^4 is adapted to engage. This pawl is mounted on a short rock-shaft p^5 , passing 35 through one of the side pieces of the frame a and carrying a crank p^6 inside of the frame, the end of which is adapted to be struck by the lug q' , formed on the hub of the operating-lever t . When the arm p swings to the 40 left to the limit of its stroke, the pawl drops behind the shoulder p^3 and prevents any return movement of the arm until such time as lug q' strikes the crank p^6 and throws the pawl out of engagement with the shoulder. 45 50 The rack-bar l carries a cross-head l^2 to limit its movement to the right.

Upon the rear of the die-head d is fixed a block u , provided with two vertical passages, in which are fitted two rods $u' u'$, respectively, said rods being connected across the top by a bar u^2 and across the bottom by plate u^3 , forming a rectangular frame adapted to slide vertically in the block. The downward movement of this frame through the block is 55 limited by a set-nut u^4 , and a spring u^5 is arranged to force the frame to its lowest position. To the under side of the plate u^3 are fixed two brackets $u^6 u^6$, having ledges around to support and guide the two edges, respectively, of the strip s . When the die-head d is elevated and the rectangular frame $u' u^2 u^3$ is at its lowest position, the passage of the

strip s through the brackets u^6 is in a direct line with the grooves d^3 in the bar d' . When the die-head lowers and before it strikes the anvil, the brackets u^6 strike a table v and the rectangular frame $u' u^2 u^3$ is caused to slide through block u as the die-head continues its movement downward. To the front edge of this table v is fixed a transverse knife-blade 75 u , which, together with the rear edge or end of the bar d' , form a shears, the plane of cut being above the plane where the meeting surfaces of the die and anvil come together and coincident with the surface of table v . 80

The strip s after leaving the wheel g' passes directly and unsupported to the passage in the brackets u^6 and ends in the plane of the knife-blade. In the operation of the machine the treadle-lever T has a backward-and-return movement. As shown in the drawings, it is making its return movement, being impelled by a weight or spring. (Not shown.) The parts of the machine are shown in the position when the feeding of the strip to the die is just beginning. The pin in the end of lug r engages with the end of the slot in the link q , moving the latter in the direction of the arrow, thus swinging the crank p^2 and arm p in the same direction. By reason of the engagement between arms p and o the latter is caused to swing on its pivot B and pull rack-bar l to the left. This rotates pinion k , and by reason of its engagement with shaft g , through the pawl and ratchet, wheel g' is rotated in a direction to send the strip s forward, which it does a distance determined by the position of the pivot in the slots of the arms o and p . In thus feeding the end of the strip passes from the passage in brackets u^6 into the passage or grooves d^3 in the die. At the end of the feeding-stroke pawl p^4 drops behind the shoulder p^3 and prevents any reaction or return movement of the feeding devices while the next step in the operation is taking place. The treadle T stops at the end of the feeding-stroke and is then returned to the right or to the rear by the foot of the operator. This movement carries the die-head d downward, the strip s moving with it until the brackets u^6 strike table v , at which instant the knife-blade comes in contact with the strip, and by the continued movement of the die-head the strip is severed, the cut-off portion being carried downward onto the corner of the box, over which it is bent, and the teeth on the back of the strip forced into the converging sides of the box to hold the strip securely in place. While the die is thus proceeding downward to do its work, the pin in the end of arm r is traveling through the slot in the link q , and consequently imparting no motion thereto, but as soon as lug q' on the hub strikes the crank p^6 and throws pawl p^4 out of engagement with shoulder p^3 the spring p^y comes into play and carries arms o and p with their connections to the left, thus rotating the pinion in the reverse direction to its previous movement, the pawl slipping loosely over the 90 95 100 105 110 115 120 125 130

ratchet and the feeding-wheel g' remaining stationary. As soon as the brackets u^6 leave the table v in the upward movement of the die-head, the pin in the end of the arm r again strikes the end of the slot in link q and the strip commences to feed into the die, the feeding movement ending when the die-head reaches the limit of its upward movement. The strip is therefore being fed into the die 10 while the latter is in motion.

It will be understood that the boxes operated upon by this kind of machine are usually made of pasteboard, and that the metallic strips applied thereto are intended to reinforce the corners.

The boxes are handled by the operator of the machine who saddles them upon the anvil and shifts from one corner to another between the strokes of the machine.

20 It is evident that the invention herein described is as well adapted for a power-driven machine as for one operated by foot. Any skilled mechanic can make the necessary changes for operating the machine by power.

25 Having thus described my invention, I claim—

1. In a box-binding machine, the combination of a reciprocating die having a passage for the binding-strip, a guide for the binding-strip carried by said die and movable with respect thereto, and a knife located between the die and guide for severing the strip as set forth.

2. In a box-binding machine, the combination of a reciprocating die having a passage for the binding-strip, and a guide for the binding-strip carried by said die, and movable with respect thereto, as set forth.

3. In a box-binding machine, the combination of a reciprocating die having a passage for the binding-strip, a guide for the binding-strip carried by said die and movable with respect thereto, a stop limiting the movement of the guide, and a stationary knife arranged 45 at the level of the stop and between the guide and the die, substantially as described.

4. In a box-binding machine, the combination of a reciprocating die provided with a passage for the strip, a feeding device for the binding-strip, an automatically-adjusting guide for the end of the binding-strip, located between the feeding device and the die, whereby the strip is properly directed into the passage in the die, for the purpose set forth.

55 5. In a box-binding machine, the combina-

tion of a feeding device for the binding-strip, a reciprocating die provided with a passage for the strip, an automatically-adjusting guide for the end of the binding-strip, located between the feeding device and the die and 60 a knife for severing the strip located between the guide and die substantially as described.

6. In a box-binding machine, the combination of a reciprocating die provided with a passage for the binding-strip, a movable frame 65 mounted in guides suitably fixed to the die, a passage for the binding-strip located in said frame, and means whereby the passage in the guide is brought in line with the passage in the die, substantially as described. 70

7. In a box-binding machine, the combination of a reciprocating rack-bar, a feeding-wheel driven thereby, a pivoted slotted arm connected with said rack-bar, another pivoted and slotted arm adjustably pivoted to 75 the first and means for swinging the second slotted arm on its pivot to thereby drive the feeding-wheel, substantially as described.

8. In a box-binding machine, the combination of a reciprocating rack-bar, a feeding-wheel driven thereby, a pivoted and slotted arm connected with said rack-bar, another pivoted and slotted arm adjustably pivoted to the first, and means for swinging the second slotted arm on its pivot to thereby drive 85 the feeding-wheel, and a detent preventing reaction of the arm when it has reached the end of its stroke, substantially as described.

9. In a box-binding machine, the combination of a reciprocating rack-bar, a feeding-wheel driven thereby; a pivoted and slotted arm connected with said rack-bar, another pivoted and slotted arm adjustably pivoted to the first, and means for swinging the second slotted arm on its pivot to thereby drive 95 the feeding-wheel, a detent preventing reaction of the arm when it has reached the end of its stroke and means for releasing the detent, substantially as described.

10. In a box-binding machine, the combination of the feeding-wheel for the binding-strip, the rack-bar l , arms o and p pivoted together, slotted link q and crank-arm r , for the purpose set forth.

In testimony whereof I subscribe my signature in presence of two witnesses.

CHAS. LEFFLER.
